C. G. HAWLEY
LOCOMOTIVE FIRE BOX

Filed May 13, 1922

Patented July 10, 1928.

1,676,732

UNITED STATES PATENT OFFICE.

CHARLES GILBERT HAWLEY, OF CHICAGO, ILLINOIS, ASSIGNOR TO LOCOMOTIVE FIRE-
BOX COMPANY, OF CHICAGO, ILLINOIS, A CORPORATION OF DELAWARE.

LOCOMOTIVE FIRE BOX.

Application filed May 13, 1922. Serial No. 560,663.

My invention relates to locomotive boilers and its object is to increase the capacity, efficiency and durability of such boilers. A special object of the invention is to provide and improve water-steaming-and-circulating attachments that may be built into or attached to any locomotive boiler firebox and which shall serve to greatly increase the effective heating area thereof, and further to promote a vigorous fore-and-aft circulation of all of the water in the boiler; and, a further object of the invention is to provide an attachment of the class mentioned which shall be of simple and economical construction and which shall be so related to the complementary firebox as to obviate all of the usual difficulties growing out of the varying degrees of expansion and contraction taking place in the different parts of the firebox. Still another object of the invention is to provide a water-steaming-and-circulating attachment, or rather pair of attachments, for installation within a locomotive firebox and which shall constitute an effective fire arch therein and also serve to subdivide the firebox flame body and thus increase the radiant area of the flame body.

My invention comprises a pair of oppositely formed hollow water-steaming-and-circulating walls which are disposed between the sides and crown of the firebox, drawing water from the side water legs of the boiler and delivering the same upon the top of the firebox crown; all as hereinafter described and pointed out in the appended claims.

The invention will be readily understood on reference to the accompanying drawings, which form a part of the specification and in which Fig. 1 is a transverse vertical section of a locomotive firebox embodying my invention; Fig. 2 is an enlarged vertical transverse section of a portion of the firebox and one of the water-circulating members shown in Fig. 1; Fig. 3 is like unto Fig. 1, but shows water-circulating members of a different shape; Fig. 4 is a sectional detail illustrating my preferred construction of the water-circulating device or member; Fig. 5 is a sectional view thereof on the line 5—5 of Fig. 4; Figs. 6 and 7 are vertical longitudinal sections of locomotive fireboxes of two kinds, showing the different side elevational shapes that the water-circulating elements may assume; Fig. 8 is a sectional detail on any of the lines 8—8 of the different

figures, and Fig. 9 is a partial view of one of the flanged ends of either of the members shown.

As shown in the drawings, the nature of my invention is such as to comprise two oppositely formed water-circulating walls somewhat in the form of brackets and which extend from each side sheet of the firebox to the crown sheet thereof, opening through both, so that water is drawn from the side legs of the firebox and discharged upon the top of the firebox. These walls are hollow brackets, as indicated. They partake of many different forms, all serving the same purpose, but of different shapes and dimensions best suited to respective fireboxes. I have shown only a few of such shapes and only enough to point out the essentials of the invention.

The familiar parts of a locomotive boiler and firebox will be recognized as follows: 2 is the barrel of the boiler; 3, the firebox shell or wrapper, including the throat plate 3' and back-head 3''. The firebox proper comprises the flue sheet 4, the side sheets 5, 5, the crown sheet 6 and the back sheet 7, the latter containing the door opening 8. The foundation or mud ring is shown at 9. No attempt has been made to illustrate the grate. The firebox of Fig. 7 differs from Fig. 6 in that it is provided with a so-called combustion chamber 10. The flues of the boiler are marked 11. As usual, the shell and firebox are connected by numerous stay-bolts 12. The portions 13 are known as the side water legs of the boiler and the space 14 above the firebox is the water and steam space of the boiler, the normal water level being depicted by the line 14'.

Referring now to Figs. 1 and 2: The water-circulating members or hollow walls above referred to, as clearly depicted in Figs. 1 and 3, are reversely or oppositely placed and positioned in the firebox. As shown, there are two of them. Each wall comprises a lower portion A¹, an upper portion A² and an intermediate or curving knuckle portion A³, and each hollow wall is from three to four inches in thickness, containing the water space or passage A⁴, which, at the bottom, communicates with the water leg 13 and at the top communicates with the water and steam space 14, as very clearly shown in Figs. 2 and 4. The lower portion A¹ is not horizontal, but, starting at a point 15 some

distance away from the flue sheet 4, extends upwardly and rearwardly to a higher point 16 on the side sheet 5. Throughout this distance the lower end is open to the side leg 13. The upper portion A² occupies a vertical, or substantially vertical, plane in the firebox and opens through the crown sheet, from a point 17 to a point 18 thereof. The knuckle portion A³ obviously serves to unite the upper and lower portions, and in every case is formed upon a generous radius or curve for the purpose of absorbing differences of expansion or contraction.

As indicated in Figs. 6 and 7, the upper portions A² of the members may partake of various shapes, to the end that the opening 17-18 may always exceed the opening 15-16 in size. I much prefer this relation in order that there shall be ample outlet for the water and steam at the top; also for the reason that by extending the upper portion the heating surface is similarly extended, with obvious benefit to the firebox. In brief, I prefer the shapes illustrated in Figs. 6 and 7, although smaller shapes may have the advantage of calling for smaller plates.

Each member comprises two sheets 19 and 20, connected by numerous short stay-bolts 21. The edges 22 of these sheets are flanged or brought together as well shown in Fig. 8, the seam being completed by autogenous weld 23. See also Figs. 2 and 4. At the upper and lower ends the sheets are flared outwardly to form the terminal flanges 24, which respectively are made to conform to the side and crown sheets of the firebox. The flanged ends occupy openings formed therefor in the firebox sheets and are united thereto by autogenous welds 25. These may be lap-welds, as shown in Fig. 2, or butt-welds, as shown in Fig. 4. By preference certain of the stay-bolts are placed in the wide terminal flanges of the member in order that the member may be directly connected with the wrapper or shell 3 of the firebox.

For the construction illustrated in Figs. 1 and 2 (Figs. 6 may also be considered) I provide the firebox with a single arch supporting tube 26. This and the inner walls of the members A serve to support a sectional firebrick arch 27, which normally occupies the space between the two water-circulating elements. With the parts 27 the members complete a very effective fire arch or baffle within the firebox.

To avoid the use of a supported arch tube the knuckle portions A³ of the two members may be brought more closely together, as shown in Fig. 3. The space between the members is then occupied by a single row of firebrick 28. A space of not less than twelve inches should be allowed between the members in order that (the brick being removed) a workman may pass forward between them

to do any necessary work upon the flue sheet of the boiler.

A marked difference will be observed between Figs. 2 and 4. In Fig. 2 the water-circulating member is shown to be stay-bolted throughout, whereas in Fig. 4 it will be noted that the stay-bolts are omitted in the knuckle portion A³. Thereby the flexibility of the member is increased, providing for the easy absorption of all expansion and contraction stresses. The only stay-bolts used in this section are the stay-bolts 21' at the edges of the members, these being required to protect the weld 23 (see Fig. 5). The curved portions of the knuckle are "self supporting" and retain their form against the internal pressure of the boiler. The extent of the free knuckle to be employed is determined by the thickness of plates 19 and 20 and the pressure to be carried by the boiler.

These water-circulating members are preferably made from sheets of the same kind and thickness as those employed in making the side and crown sheets of the firebox, but my invention comprehends the employment of different materials. It is entirely feasible to use copper water-circulating members of this form in fireboxes which are composed of steel sheets.

The wash-out plugs 29 are provided in the wrapper or shell of the boiler opposite the upper and lower ends of the water-circulating members and upon the removal of these plugs it is an easy matter to wash and clean the internal surfaces of the members. They should occasionally be bombarded or bobbed upon the exterior to dislodge hard scale.

When the boiler is under fire and the firebox virtually filled by the body of flame 105 these members obviously present heating surfaces of the most advantageous sort and position. The evaporation of the water in the members induces a rapid flow of water there-through. This water is drawn from the side water legs of the boiler, which spaces are replenished from water which flows rearwardly from the barrel of the boiler. The wide open tops of the members provide for the easy disengagement of all 115 steam evolved therein and the hot water fountaining therefrom must needs find its way forward to the front end of the boiler. Thus a pronounced and vigorous fore-and-aft circulation is set up within the boiler, with marked improvement in the steaming 120 efficiency of every square foot of heating surface therein.

In event of low water in the boiler, the fountains rising from the members serve to 125 cover and protect the crown sheet of the firebox and prevent a disastrous explosion.

Having thus described my invention, I claim as new and desire to secure by Letters Patent:

1. A locomotive boiler and its stay bolted internal firebox, in combination with two longitudinally disposed and transversely opposed flat faced and stay bolted bracket-shaped water circulating walls within said firebox, each said wall having a transverse lower portion that is rearwardly and upwardly inclined and, at its outer end, attached to its respective side of the firebox, each said wall having an upright upper portion which has its top attached to the top of the firebox, and, the upright portions of the two walls being separated by a passage which affords access to the front of the firebox.
2. A locomotive boiler and its stay bolted internal firebox, in combination with two longitudinally disposed and transversely opposed flat faced and stay bolted bracket-shaped water circulating walls within said firebox, each said wall having a transverse lower portion that is rearwardly and upwardly inclined and, at its outer end, attached to its respective side of the firebox, each said wall having an upright upper portion, the top of which is of a length greater

than said outer end of the transverse lower portion and which longer top is attached to the top of the firebox, and the upright portions of the two walls being separated by a passage which affords access to the front of the firebox.

3. A locomotive firebox having side sheets that contain upwardly and rearwardly inclined slots, and, having a crown sheet which contains two spaced-apart longitudinal slots of greater length than those in the side sheets, in combination with oppositely disposed bracket-shaped water circulating walls having upper and lower parts which communicate with and correspond to the slots in respective crown and side sheets.

4. In a locomotive boiler as defined in claim 1, each said wall being staybolted throughout its extent, except in the bend portion joining its transverse and upright portions.

In testimony whereof, I have hereunto set my hand this 6th day of May, 1922.

CHARLES GILBERT HAWLEY.
